UNITED STATES PATENT OFFICE

CARL F. HAAS, OF LAKEWOOD, OHIO, ASSIGNOR TO WESTINGHOUSE ELECTRIC & MANUFACTURING COMPANY, A CORPORATION OF PENNSYLVANIA.

DESIGN FOR A HEAD FOR A LIGHTING UNIT

Application filed September 20, 1930. Serial No. 37,029. Term of patent 14 years.

To all whom it may concern:

Be it known that I, CARL F. HAAS, a citizen of the United States, residing at Lakewood, in the county of Cuyahoga and State of Ohio, have invented a new, original, and ornamental Design for a Head for a Lighting Unit, of which the following is a specification, reference being had to the accompanying drawings, constituting a part hereof.

Figure 1 is a front elevational view, and

Fig. 2 is a side elevational view of a head for a lighting unit showing my new design.

I claim:

The ornamental design for a head for a lighting unit substantially as shown.

In testimony whereof, I have hereunto subscribed my name this 3rd day of September, 1930.

CARL F. HAAS.
